(57) **CLAIM**

The ornamental design for a packaging system for oral strips, as shown and described.

DESCRIPTION

FIG. 1 is a front perspective view of a packaging system for oral strips, showing an outer package in a closed position; FIG. 2 is a front perspective view thereof, illustrated with the outer package in an open position to reveal three middle packages contained in pockets of the outer package, the middle packages illustrated in a closed position; FIG. 3 is an exploded front perspective view of FIG. 2; FIG. 4 is an exploded front perspective view of FIG. 3, illustrated with each of the three middle packages in an open position to reveal ten single packages, the single packages illustrated in a closed position; FIG. 5 is an exploded front perspective view of FIG. 4, illustrated with a first of the plurality of single packages of each middle package in an open position to reveal an oral strip; FIG. 6 is an exploded front elevational view of the outer package, one of the middle packages, and one of the single packages, the other middle packages and single packages omitted for clarity of illustration; FIG. 7 is an exploded front elevational view of FIG. 6, except with the packages in the open position; FIG. 8 is an exploded left-side elevational view of FIG. 6; FIG. 9 is an exploded left-side elevational view of FIG. 7; FIG. 10 is an exploded rear elevational view of FIG. 7; FIG. 11 is an exploded top plan view of FIG. 6; FIG. 12 is an exploded top plan view of FIG. 7; FIG. 13 is an exploded bottom plan view of FIG. 6; and, FIG. 14 is an exploded bottom plan view of FIG. 7. The broken lines in the figures depict portions of the packaging system for oral strips that form no part of the claimed design.
